UNITED STATES PATENT OFFICE.

THOMAS SAPP, OF LONDON, ENGLAND.

SIGN AND ADVERTISING DEVICE.

Application filed May 29, 1922. Serial No. 564,393.

To all whom it may concern:

Be it known that I, THOMAS SAPP, a British subject, residing at 24 Essex Street, Strand, London, W. C. 2, England, have invented certain new and useful Improvements in Signs and Advertising Devices, of which the following is a specification.

This invention relates to an improved form of glass for use in signs, and is applicable to box signs using an artificial source of illumination within the sign and to tablet signs having a reflective backing and rendered visible by means of natural light or artificial light from casual sources such as street lamps.

According to the invention I provide a glass panel bearing parallel ribs, flutings, corrugations or the like on each surface, the two series of parallel ribs being transverse to each other, the panel so arranged that the light reaching the eye of the observer from the sign whereby the design is visible is constrained to pass through said panel.

The invention is illustrated in the accompanying drawings in which,

Figure 1 shows a front view of a tablet sign, and

Figure 2 is a cross section on the line *a—a* of Figure 1, and

Figure 3 illustrates a diagrammatic section of a box sign.

Referring now to the drawing, the improved tablet sign comprises a frame 1 carrying a glass panel 2 provided on each of its surfaces with a parallel series 3, 4 of ribs, corrugations, flutings or the like. In the form illustrated, the series 3 of corrugations on the front surface of the glass is horizontal, and the series 4 of corrugations

on the rear surface of the glass is vertical. The rear surface of the glass is mirrored, and the front surface is partly rendered opaque, leaving a transparent design represented in the drawing by the letters F. A. S.

It will be appreciated that the sign is chiefly rendered visible by light reflected from the mirrored rear surface of the glass through the transparent design F. A. S. and that such light traverses the glass panel in a manner such that both surfaces deflect it.

Alternatively, I may use a separate reflective surface situated behind the glass panel instead of mirroring the rear surface of the panel, and I may further employ a separate means for masking the panel so as to display the design instead of applying

opaque material to the actual surface of the glass.

Referring now to Figure 3, I here illustrate a box sign provided with a separate source of illumination consisting of an electric lamp. In the front of the sign is provided a glass panel 2 having horizontal corrugations 3 on its front surface. The front surface in this case also may be partly covered with an opaque material leaving a transparent design. The rear surface is formed with vertical corrugations 4. It will be seen that the visibility of the sign necessitates light reaching the eye of the observer through the glass panel 2. In all cases where I describe the use of opaque material on the surface of the glass I may if desired use translucent paint whereby the background of the design instead of being a "dead" colour will appear warm and live owing to the transmission therethrough of a certain amount of light reflected from the mirrored surface.

It is to be understood further that if desired the lettering of the design may be opaque or covered, and the background clear.

The invention is further applicable to signs not bearing designs such as red reflexive discs adapted to be fitted on the backs of automobiles, cycles and the like. In such cases I use a piece of glass having the two transverse series of corrugations on its two surfaces and the rear surface being mirrored, the red tint being obtained either by means of the use of tinted glass or by the application of translucent red paint on the front surface.

I claim:—

1. In a sign a glass panel having a series of parallel ribs on its front surface and a series of parallel ribs on its rear surface, the two series being transverse to each other, the rear surface of the glass being mirrored, and the front surface being partly rendered opaque to display a design.

2. In a sign a glass panel having a series of parallel ribs on its front surface and a series of parallel ribs on its rear surface, the two series being transverse to each other, means for masking a portion of the panel so as to display a design, and a mirrored surface at the rear of the panel for reflecting light through the plate.

3. In a sign, a glass panel having a series of parallel corrugations on the front surface,

and a series of parallel corrugations on the rear surface at right angles to those on the front surface, the front surface of said plate having a predetermined sign design outlined thereon, and the rear surface being mirrored, the angular arrangement of the ribs serving to reflect the light from different sources for illuminating the sign.

4. A sign, including a glass panel having a series of parallel corrugations in the front surface, and a series of parallel corrugations in the rear surface disposed transversely to the first mentioned corrugations, a translucent sign design formed on the front surface of said plate, and the back surface being mirrored so that light from various sources is reflected for illuminating the sign.

5. A sign including a glass panel formed with ribs on the front and rear surfaces to refract light, the rear surface being provided to refract light, the rear surface being pro-

vided with a reflecting surface, and means for rendering a portion of the ribbed front surface opaque to display a design.

6. A sign including a glass panel formed with ribs on the front and rear surfaces for refracting light, a reflecting surface at the rear surface of the panel, and a translucent screen at the front surface of the plate displaying a sign design, whereby light from a casual source is reflected for illuminating the sign.

7. A sign, including a glass panel formed with ribs on the front and rear surfaces to refract light, the rear surface being provided with a reflecting surface, means at the front surface of the plate for displaying a design, and means for coloring the reflected light from said reflecting surface.

In testimony whereof I affix my signature.
THOMAS SAPP.
